5 Claims. (Cl. 230—145)

ABSTRACT OF THE DISCLOSURE

The present invention relates to a rotary piston internal combustion engine of the type which has an exhaust gas collecting chamber between a side wall of the engine housing and the piston journalled in bearing means in said side wall, while gear means are respectively arranged near said chamber means and are respectively connected to said side wall and said piston for kinematically controlling the piston.

The invention is characterized primarily in that the said bearing means and gear means are sealed with regard to said exhaust gas collecting chamber means by a three sectional labyrinth seal with the first section thereof connected to said side wall, the second section thereof connected to said piston, and with the third section arranged between said first and second sections, said first and second sections having circular teeth respectively cooperating with oppositely extending teeth of said third section.

The present invention relates to a rotary piston internal combustion engine, especially circular piston internal combustion engine in which the piston profile is determined by a trochoid, preferably epitrochoid, while accordingly, the housing profile follows the outer enveloping curve of the trochoid. The present invention is particularly directed to an engine of the above mentioned type, in which for purposes of realizing the four-stroke cycle method, a piston is employed, the circumference of which has a number of axis-near zones or lobes divisible by 2, said piston between two successive axis-near zones being provided with an inlet-control opening and an outlet-control opening. The inlet and outlet control openings are respectively connected through passages or the like in the piston with inlet and outlet openings provided in the end-faces of the piston and directly or indirectly leading into a sealed collecting chamber of the housing, the seal of which is effected in a contact-free manner through a labyrinth. Such engine is disclosed e.g. in assignee's patent application filed Apr. 17, 1967, under Ser. No. 631,459 and based on German application Ser. No. K 59,043 filed Apr. 20, 1966.

With a rotary piston internal combustion engine of the above mentioned type, the collecting chambers may have connected thereto simple conduit means leading toward the outside. However, the said collecting chambers must be sealed with regard to the transmissions and bearings. This seal causes considerable difficulties because the sealed elements or parts have to move relative to each other with an eccentricity.

It is, therefore, an object of the present invention to provide a rotary piston internal combustion engine, especially circular piston internal combustion engine, with means which will properly seal the transmissions and bearing portions relative to the gas collecting chambers.

It is another object of this invention to provide an engine as set forth in the preceding paragraph in which the seal will be simple in construction and highly effective.

These and other objects and advantages of the in-

2

vention will appear more clearly in the following specification in connection with the accompanying drawing, in which—

FIG. 1 diagrammatically illustrates a section through 5 a portion of a circular piston internal combustion engine provided with a seal according to the present invention.

FIG. 2 illustrates on a somewhat larger scale than FIG. 1 the way in which the labyrinth seal according to FIG. 1 operates.

10 The labyrinth seal, according to the present invention, is characterized primarily in that it comprises three sections of which one section is connected to the piston, while a second section is connected to the eccentric shaft, and a third section is connected to the sidewall of the housing, the second or intermediate section with labyrinth forming teeth engaging correspondingly formed counter-teeth of the two other sections.

Referring now to the drawings in detail, FIG. 1 shows 15 a circular piston internal combustion engine with a piston 1, the profile of which is determined by an epitrochoid, while the inner contour of the profile of the housing follows the outer enveloping curve of the epitrochoid. The piston 1 is journalled on an eccentric shaft 3. For kinematically controlling the piston 1, there is provided 20 a pinion 4 connected to the piston 1 and cooperating with a hollow gear 5. The bearing for the eccentric shaft in the housing sidewall 6 is designated with the reference numeral 7. The bearing 7 and the transmission for kinematically controlling the piston are sparated from the 25 exhaust gas controlling chamber 8 by a labyrinth seal.

As will be seen from the drawing, this labyrinth seal 30 comprises two sections of which the section 9 is connected to the piston 1, while the section 10 is connected to the eccentric shaft 3, and the section 11 is connected to the 35 sidewall 6 of the housing 2. With this arrangement of the labyrinth sections, the labyrinth teeth 12 form annular members or rings which can easily be produced as bodies of revolution on a lathe or automat. According to the embodiment shown in FIG. 1, the labyrinth, section 11 forms 40 a single integral piece with the hollow gear 5. For purposes of improving the sealing effected, the labyrinth sections 9 and 10 are provided with splash rings 13, 14. Moreover, the cylindrical seat of the labyrinth section 9 is provided with a seal 15.

45 The operation of the labyrinth seal is best seen from FIG. 2, which shows the labyrinth seal on a somewhat larger scale than FIG. 1. However, in contrast to FIG. 1, the labyrinth section 11' and the hollow gear 5 consist 50 of two pieces. Furthermore, a splash ring 16 is interposed between the hollow gear 5 and the labyrinth section 11.

As will be evident from the above, the labyrinth seal, according to the present invention, permits an easy bridging of the eccentricity of the movable parts relative to the 55 stationary parts. Moreover, all sections of the labyrinth seal are of a simple design so that they can easily be produced on corresponding machine tools.

It is, of course, to be understood that the present invention is, by no means, limited to the illustrated discharge side of a circular piston internal combustion engine, but 60 can also be provided with all of those advantages on the inlet side of the engine. Furthermore, the invention is not limited to a rotary piston internal combustion engine but can also be employed for circular piston internal combustion engines.

65 What I claim is:

1. A rotary piston internal combustion engine, especially circular internal combustion engine, with a piston profile determined by a trochoid and with a housing having an 70 inner peripheral profile following the enveloping curve for said trochoid, which includes: side wall means forming part of said housing, bearing means located in said side

wall means, an eccentric shaft rotatably journaled in said bearing means and supporting said piston, control means respectively connected to said side wall means and said piston for kinematically controlling the movement of said piston, exhaust gas collecting chamber means arranged between said side wall means and said piston, and labyrinth sealing means interposed between said bearing means and said control means on one hand and said chamber means on the other hand for sealing said bearing means and said control means with regard to said chamber means, said labyrinth sealing means comprising a first section connected to said side wall means and provided with circular tooth means facing toward said piston, said labyrinth sealing means comprising a second section connected to said piston and provided with circular tooth means facing toward the tooth means of said first section, said labyrinth sealing means also comprising a third section connected to said eccentric shaft and having oppositely directed circular tooth means interposed between said first and second sections and in respective sealing arrangement with the tooth means thereof.

2. An engine according to claim 1, in which each of said labyrinth sealing sections has a plurality of radially spaced teeth.

3. An engine according to claim 2, in which the cir-

cular teeth on one side of said third section are radially offset with regard to the circular teeth on the opposite side of said third section.

5. An engine according to claim 1, in which said control means include a gear ring with inner teeth forming an integral part with said first section and also include gear means connected to said piston and meshing with said gear ring.

10 10. An engine according to claim 1, in which said control means include a gear ring interposed between and firmly connected to said side wall means and said first section and also include gear means connected to said piston and meshing with the teeth of said gear ring.
